Patented Mar. 5, 1918.

FIG. 1. 3

FIG. 2. 4

Inventor
Louis Schissel,
By his Attorneys
Edgar Gate & Co.

UNITED STATES PATENT OFFICE.

LOUIS SCHISSEL, OF BROOKLYN, NEW YORK.

ARTICLE OF MANUFACTURE.

1,258,470.

Specification of Letters Patent. Patented Mar. 5, 1918.

Application filed April 30, 1917. Serial No. 165,310.

To all whom it may concern:

Be it known that I, LOUIS SCHISSEL, a citizen of the United States, and residing at Brooklyn, in the county of Kings and State 5 of New York, have invented certain new and useful Improvements in Articles of Manufacture, of which the following is a specification, such as will enable those skilled in the art to which it appertains to

10 make and use the same.

This invention relates to articles of manufacture, and particularly to devices of this class known as toys, and the object thereof is to provide an improved device of this 15 class especially designed to amuse children at Christmastime, but which may be used for the purpose specified at any time or place.

The invention is fully disclosed in the following specification, of which the accompanying drawing forms a part, in which the separate parts of my improvement are designated by suitable reference characters in each of the views, and in which:—

25 Figure 1 is a front view of my improved article of manufacture;

Fig. 2 a similar view but showing the parts in a different position;

Fig. 3 a section on the line 3—3 of Fig. 1;

30 Fig. 4 a section on the line 4—4 of Fig. 2; and,

Fig. 5 a section on the line 5—5 of Fig. 1.

My improved article of manufacture, or toy device, is preferably oblong and rectangular in form as shown at *a* in Figs. 1 and 2, and comprises a frame composed of similar side members *a*² and top and bottom members *a*³ and *a*⁴, and the frame is provided with a front facing *a*⁵ composed of 35 cardboard or similar material and a back facing *a*⁶ of cardboard or similar material, and between which is a space *a*⁷ which extends from the top to the bottom of the frame and in which is mounted a movable 40 shutter member *b* composed of cardboard or similar material, and the shutter member *b* is connected with the top of the frame by an elastic cord or cords *c* and non-elastic cord or cords *d* are connected with the bottom 45 of the shutter member and passed out through the bottom of the frame, and provided with a knob or handle *d*², and by grasping said knob or handle the shutter member *b* may be drawn down to the bottom 50 of the frame as shown in Fig. 4, and when the pull on the cord or cords *d* is re-

leased the shutter member *b* will be drawn back into the center or top portion of the frame, as shown in Fig. 3.

The front facing *a*⁵ is provided in the bottom portion thereof with a central opening *e* which represents a fireplace opening and back of which the back facing *a*⁶ is painted, printed or colored to represent a fire-grate *f*, andirons *f*² and a fire *f*³. 65

Above the fireplace opening *e* in the front facing *a*⁵, said front facing is printed, painted or stamped to represent a mantel *g*, and at the opposite sides of said fireplace opening to represent side panels *g*² and around 70 the fireplace opening to represent the usual tile wall, and above the mantel *g*, the front facing *a*⁵ is printed, painted or stamped to represent tile *h* within the central portion of which is a space *h*² in which is placed 75 the legend "Santa Claus in the chimney, what has he in his bag for you".

The front of the shutter member *b* is provided with a picture of Santa Claus with his bag as shown at *i*, and at the back of the 80 device and extending, in the construction shown, from the top to the bottom thereof is a pocket device *j* made in the manner of a bellows and comprising a back member *j*² secured to the back of the frame and the 85 back facing *a*⁶, and a front member *j*³, and the pocket device *j* is designed for use as a container for toys of various kinds or classes.

As hereinbefore stated my improved 90 article of manufacture is designed to amuse and entertain the young and may be kept on hand for sale wherever such devices are marketed and purchasers may buy the same, and at the same time purchase toys of various kinds and classes by which the pocket device *j* which is in the form of a paper bag may be filled, and by pulling on the cord or cords *d* the shutter device *b* with a picture of Santa Claus thereon may be 95 made to descend into the fireplace as shown in Fig. 2, and said device will be withdrawn above said fireplace when the pull on the cord or cords *d* is released. 100

My improved article of manufacture may 105 be made of any desired material and any preferred dimensions, and while I have shown and described the design or decoration for the front thereof which I prefer, my invention is not limited to such design or 110 decoration, and changes in and modifications of the details of construction herein

shown and described may be made, within the scope of the appended claims, without departing from the spirit of my invention or sacrificing its advantages.

5 Having fully described my invention, what I claim as new and desire to secure by Letters Patent, is:—

1. A device of the class described comprising an oblong rectangular frame having 10 front and back facings, the bottom portion of the front facing being provided with an opening rearwardly of which the back facing is provided with the representation of a fireplace and a vertically movable shutter device mounted in said frame and connected with the top thereof by an elastic cord or cords and the bottom of which is provided with a non-elastic cord which passes downwardly through the bottom of 15 the frame, and said shutter device being provided with a picture of Santa Claus.

2. A device of the class described comprising an oblong rectangular frame having front and back parts, the bottom portion 20 of the front part being provided with an opening representing a fireplace and a vertically movable shutter device mounted in said frame and connected with the top thereof by an elastic cord or cords and the bottom of 25 the frame, and said shutter device being provided with a picture of Santa Claus.

bottom of which is provided with a non- 30 elastic cord which passes downwardly through the bottom of the frame.

3. A device of the class described comprising an oblong rectangular frame having front and back parts, the bottom part of 35 the front being provided with an opening representing a fireplace and rearwardly of which the back part is provided with the representation of a grate and andirons, the front part being also provided above said 40 opening with the representation of a mantel and at the opposite sides thereof with panels, and a vertically movable shutter device mounted in said frame and connected with the top thereof by an elastic cord or 45 cords and the bottom of which is provided with a non-elastic cord which passes downwardly through the bottom of the frame, and said shutter device being provided with a picture representing Santa Claus. 50

In testimony that I claim the foregoing as my invention I have signed my name in presence of the subscribing witnesses this 27th day of April 1917.

LOUIS SCHISSEL.
